DESIGN FOR A LAMP SHADE SUPPORT

Robert Beardsley and James P. Martin,
Wilmette, Ill.

Application April 28, 1941, Serial No. 100,647

Term of patent 3½ years

To all whom it may concern:

Be it known that we, Robert Beardsley and James P. Martin, both citizens of the United States, residing at Wilmette, in the county of Cook and State of Illinois, have invented a new, original, and ornamental Design for a Lamp Shade Support, of which the following is a specification, reference being had to the accompanying drawing, forming part thereof.

In the drawing:

and

Figure 3 is a bottom plan view thereof, with the upper portion of the adjustable member omitted.

We claim:

The ornamental design for a lamp shade support, as shown.

ROBERT BEARDSLEY.
JAMES P. MARTIN.
